UNITED STATES PATENT OFFICE.

ALFRED P. ROTH, OF NEW YORK, N. Y.

DESIGN FOR A SOUNDING-BOARD FOR HARPS.

SPECIFICATION forming part of Design No. 27,276, dated June 29, 1897.

Application filed April 20, 1897. Serial No. 633,057. Term of patent 3½ years.

To all whom it may concern:

Be it known that I, ALFRED P. ROTH, of the city of New York, county and State of New York, have invented and produced a new and original Design for Sounding-Boards for Harps, of which the following is a specification, reference being had to the accompanying drawings, in which—

Figure 1 represents a face view of my newly-designed sounding-board for harps. Fig. 2 is a cross-section through the harp body on line 2 2, Fig. 1.

The leading feature of my design consists of a sounding-board for harps having a perforation, a straight side, and a pair of arched sides that join the straight side at a round and sharp corner, respectively.

A is the sounding-board of the harp, having a perforation A', a straight side a, and two arched sides b c. The arch b is struck with a larger radius than the arch c, into which it merges by a curvilinear angle d. The sides b a are joined by a round corner e, while the sides c a are joined by a sharp corner f.

What I claim is—

The design for a sounding-board for harps, substantially as herein shown and described.

ALFRED P. ROTH.
